REGULATOR FOR UNDERWATER BREATHING APPARATUS

Samuel G. Lecocq, Los Angeles, Calif., assignor to Sportsways, Inc., Paramount, Calif., a corporation of California

Filed Dec. 19, 1961, Ser. No. 67,961

Term of patent 14 years

(Cl. D83—1)

Fig. 1.

Fig. 5.

Fig. 2.

Fig. 6.

Fig. 3.

Fig. 4.

FIG. 1 is a perspective view of a regulator for underwater breathing apparatus showing my new design;

FIG. 2 is an elevational view as seen from one side of the same;

FIG. 3 is an elevational view as seen from the opposite side;

FIG. 4 is a front elevational view of the same as positioned in FIG. 1;

FIG. 5 is a top plan view; and

FIG. 6 is a bottom plan view.

The dominant features of the design reside in the portion shown in full lines.

I claim:

The ornamental design for a regulator for underwater breathing apparatus, as shown and described.
